Atty's

UNITED STATES PATENT OFFICE.

CHARLES FISHER, OF OAK PARK, ILLINOIS.

DESIGN FOR A POCKET SAVINGS-BANK.

No. 39,204.

Specification for Design.

Patented March 17, 1908.

Application filed August 1, 1907. Serial No. 386,673. Term of patent 7 years.

To all whom it may concern:

Be it known that I, CHARLES FISHER, a citizen of the United States, residing at Oak Park, in the county of Cook and State of Illinois, have invented a new, original, and ornamental Design for Pocket Savings-Banks, of which the following is a specification, reference being had to the accompanying drawing, forming a part thereof.

The drawing shows a perspective view of a pocket savings-bank in accordance with my design.

I claim:

The ornamental design for a pocket savings-bank, as shown.

CHARLES FISHER.
